PACKAGE

John P. R. Schell, Harpersville, Ala.

Application August 5, 1943, Serial No. 497,466

8 Claims. (Cl. 229—14)

This invention relates to an improved package.

In my application Serial No. 380,571, filed February 26, 1941, which has matured into Patent No. 2,361,876, I have described an improved type of package which is preferably collapsible and which includes an outer carton and an inner flexible liner which may or may not be attached to the carton. A portion of the liner extends between lips formed by flaps on the carton, and by puncturing this portion of the liner, a spout is formed through which the contents of the package may be discharged by applying pressure, which collapses the package. The inner liner is preferably formed from a single oblong sheet of wrapping material, preferably rubber hydrochloride film or other moistureproof, liquid-tight material, which is folded in half and sealed along each edge adjacent the fold to form an envelope. This envelope may be squared up to form the liner for the carton, and then after filling the package, the top of the envelope may be sealed by first pulling the opposite ends of the top opening at the portions where they are sealed in order to form a straight line opening across the top of the liner and then sealing the liner across this straight line opening which contains no folds and is only two layers of material thick from one end to the other. This forms triangular ears where the package is closed. One of these ears may be folded in in the usual way. The other ear extends between the lips of the package, and by cutting the point of it off, a suitable opening is formed for the discharge of the contents of the package. The package is designed particularly for the sale of such materials as mayonnaise, mustard, peanut butter, etc., which are consumed a little at a time and should be protected from the air and evaporation during the intervals between use.

In the present improved form of the invention, the front and back wall of the carton are collapsed toward one another, and the side walls are scored so that they collapse inwardly. The liner extends between the flap on the back wall and that portion of the flap on the front wall which forms an extension beyond the length of flap required to cover the top of the carton. The preferred form of package is constructed to be self-sealing by providing means for temporarily fastening the flap on the back wall to the flap of the front wall which covers the top of the carton.

The invention will be further described in connection with the accompanying drawing, in which

Fig. 1 is a plan view of the blank of chip board or other suitable fiber material from which the carton is formed, Fig. 2 shows the carton with the opening closed, and Fig. 3 is a view similar to Fig. 2 but with the flap on the back wall of the carton extended.

The carton comprises the front 1 and the back 2 and the side walls 3 and 4. There is a lip 5 shown in Fig. 1, which is glued to the side wall 4 in forming the carton. The manner of scoring the blank is clearly shown in Fig. 1, the double lines indicating scorings on the inner surface of the blank and the dotted double lines indicating scorings on the outer surface of the blank.

It will be noted from Fig. 1 that the top and bottom edges of the side walls are not parallel but that each forms a wide V. This causes the package to appear somewhat collapsed when first formed and before the sides have been pushed in. A package which is thus formed may be collapsed more readily than one in which the top and bottom edges of the side walls are perfectly parallel.

25 The flaps on the top and bottom of the side walls are not square cornered but together taper away from the walls so that the package may be more easily collapsed. In the preferred form there are two separate flaps at the top and bottom of each side wall, as shown in Fig. 1.

20 The flaps 6 and 7 on the bottom of the front and back wall may be of any usual design. If the flap on the back wall is to be folded over the flap on the front wall, the front flap preferably covers no more than half of the bottom of the package, and the flap on the back may advantageously cover the whole of the bottom, but, in this case, it is preferably scored down the middle so that the package may be easily collapsed. This arrangement is illustrated in the drawing.

25 The flap at the top of the front wall is composed of three portions, 10, 11, and 12. The portions 10 and 11 each cover one-half of the top of the carton, and these are divided by the scored line 13. The portion 15 of the flap forms an extension which extends beyond the top of the carton and cooperates with the flap on the back of the carton, and together with a portion 16 of the liner which extends between them, they form a spout for the discharge of the contents of the package.

30 The flap at the top of the back of the carton is composed of four portions, 17, 18, 19, and 20. The portions 17 and 18 are divided by a scored

line 22, which permits the portions 18-20 to be folded away from the portion 17, and the portions 12 and 17 form a spout between which the portion 16 of the liner extends. The portions 12 and 17 of the front and back flaps may be glued together.

After a portion of the contents of the package has been removed and it is desired to close the carton, the flap 17-20 is folded down over the top of the carton, and this folds the extension 12 back on the portion 11 of the front flap. The portion 19-20 is now slipped into the opening 25 in the front flap. The side edges of this opening are tapered toward the back of the carton, and the side edges of the portion 19 of the flap are tapered toward the back of the carton so that the portion 19 may be easily slipped into the opening 25; because of the tapered edges of the opening and the portion 19, the back flap is held firmly in the opening 25. This forms a sharp bend along the top edge of the back wall of the carton which presses the walls of the portion of the liner together and excludes the air from the package.

The closure thus formed may easily be broken by applying pressure along the line 22 of the back flap. When the catch portion of the back flap is fitted into the opening 25 of the front flap, the wide edge formed at the fold 26 does not coincide exactly with the fold 13 across the top of the front flap. This is shown in Fig. 2. This causes the fold 22 to bend outwardly somewhat, and the back flap is raised somewhat from the top of the carton at this bend. By applying pressure directly at the bend to flatten the fold 22, the back flap is flattened and thus lengthened sufficiently to force the front edge 26 of the catch into the wide front portion of the opening 25, and this quickly releases the catch.

The carton may be assembled in any usual way. The liner may be filled before it is inserted in the carton; or, as is preferable, it will be filled while within the open carton, and the four bottom flaps will be folded in by first folding in the flaps on the side walls and then the flaps 6 on the front wall and then the flap 7 on the back wall, there being adhesive on the portion of the flap 7 which overlaps the flap 6. After the package is filled, the top of the carton will be closed by heat-sealing the carton; and in the preferred form of the invention, the seal is made as above described, and two triangular ears are formed at each end of the top of the liner. These ears extend beyond the front and back walls. The ear extending beyond the front wall is folded in in the usual manner, either above or below the flaps on the side walls. The front wall is then folded over, and the portions 10 and 11 are glued to the flaps on the side walls. The extension 12 on the front flap is in this way brought flat against the portion 17 of the back flap with the triangular ear protruding between them. Preferably, the edges of the extension 12 and the flap 17 will be glued together. The back flap will then be folded down and the portion 19 caught in the opening 25. If preferred, the back flap may be folded flat against the outer surface of the top flap; and the portion 20 glued on to the exposed surface of the portion 10 of the front flap.

When the package is to be used, it is opened as shown in Fig. 3, and the point of the inner liner 16 is snipped off, or the liner is punctured in any suitable manner to allow the contents to escape. Then, as the contents are desired, pressure is applied to the front and back walls to

gradually collapse the carton, and between periods of use the carton is closed by folding the back flap over and catching the portion 19 in the opening 25.

5 The carton is so constructed that as it is collapsed, the front and back walls remain parallel to one another, and the package will stand upright at all times until it has been emptied. The side walls are scored so that they collapse inwardly as pressure is applied, and the flaps on the top and bottom of the side walls are so designed as not to hinder the collapsing of the carton or the insertion of the catch 19-20 through the opening 25.

15 What I claim is:

1. In a package formed of a bag liner and an outer carton closed at the top by a flap on the front of the carton which extends beyond the top of the carton when folded over and forms with the flap on the back of the carton an opening at the top edge of the back of the carton through which a portion of the liner protrudes, the improvement which comprises side walls, the top and bottom of which are notched by wide V's 25 which extend from the corners to the center thereof, the two side walls and the top and bottom of the package being scored so that the package may readily be collapsed with the front and back of the package being maintained in substantially parallel planes throughout the collapsing thereof and with individual flaps at the top and bottom of each half of each side wall, the edges of said flaps adjacent the front and back of the carton being tapered away from the side wall so that the package may be collapsed to a considerable extent before the edges of the flaps on the side walls contact the front and back of the package.

2. In a package formed of a bag liner and an outer carton closed at the top by a flap on the front of the carton which extends beyond the top of the carton when folded over and forms with the flap on the back of the carton an opening at the top edge of the back of the carton through which a portion of the liner protrudes, the improvement which comprises an opening in the flap on the front of the carton into which a portion of the flap on the back of the carton is adapted to fit so as to close the package and fold the front and back flaps sharply at the edge along the top of the back of the carton.

3. In a package formed of a bag liner and an outer carton closed at the top by a flap on the front of the carton which extends beyond the top of the carton when folded over and forms with the flap on the back of the carton an opening at the top edge of the back of the carton through which a portion of the liner protrudes, the improvement which comprises side walls which are notched by straight lines extending from the corners to the middle thereof.

4. In a package formed of a bag liner and an outer carton closed at the top by a flap on the front of the carton which extends beyond the top of the back of the carton when folded over and forms with the flap on the back of the carton an opening at the top edge of the back of the carton through which a portion of the liner protrudes, the improvement which comprises scorings on the top, bottom, and side walls thereof in a plane passing through the middle of the carton and parallel to the front and back thereof, some of said scoring being adapted to facilitate inward folding of the package and some being adapted to facilitate outward folding, the entire

scoring of the carton being adapted to facilitate collapse of the carton with the front and back in substantially parallel planes.

5. In a package formed of a bag liner and an outer carton closed at the top by a flap on the front of the carton which extends beyond the top of the carton when folded over and forms with the flap on the back of the carton an opening at the top edge of the back of the carton through which a portion of the liner protrudes, the improvement which comprises a catch portion on the back flap, the side edges of which taper toward the top of the back wall, and an opening in the back half of the front flap, the edges of which taper toward the back wall, which opening is adapted to receive the catch on the back flap and to hold the same.

6. In a package formed of a bag liner and an outer carton closed at the top by a flap on the front of the carton which extends beyond the top of the carton when folded over and forms with the flap on the back of the carton an opening at the top edge of the back of the carton through which a portion of the liner protrudes, the improvement which comprises a catch portion on the back flap, the side edges of which taper toward the top of the back wall, and an opening in the back half of the front flap, the edges of which taper toward the back wall, which opening is adapted to receive the catch on the back flap and to hold the same, and scorings on the side walls and the top and bottom of the carton so that the package is adapted to collapse when pressure is applied to the front and back walls.

7. In a package formed of a bag liner and an outer carton closed at the top by a flap on the front of the carton which extends beyond the top of the carton when folded over and forms with the flap on the back of the carton an opening at the top edge of the back of the carton through which a portion of the liner protrudes, the improvement which comprises side walls, the upper and lower edge of which form a wide V, with flaps on each arm of the V.

8. In a package formed of a bag liner and an outer carton closed at the top by a flap on the front of the carton which extends beyond the top of the carton when folded over and forms with the flap on the back of the carton an opening at the top edge of the back of the carton through which a portion of the liner protrudes, the improvement which comprises scorings in the middle of the top, bottom, and side walls of the package so that the package is adapted to collapse with the front and back thereof in substantially parallel planes and with the top and bottom of each side wall forming a wide V which extends from each corner to the middle of the side and with a flap on each arm of the V, and with flaps adjacent the front of the carton and fastened to the top of each side wall being cut back so that in the assembled package the inner edges of said two flaps do not in any way obstruct the opening in the top flap.

JOHN P. R. SCHELL.
